UNITED STATES PATENT OFFICE.

JOHN E. LOCK, OF LOWELL, MASSACHUSETTS.

TRAFFIC SIGNAL FOR VEHICLES.

Application filed September 14, 1926. Serial No. 135,376.

This invention relates to traffic signals for vehicles and has for an object to provide a signal embodying new and improved mechanical features and movements, insuring improved facility, accuracy and reliability in the actuation of signals.

A further object of the invention is to provide a wholly mechanical signal operating simultaneously at the front and rear of the vehicle and operated by a swaying motion of the knees of the operator.

A further object of the invention is to provide a knee operating organization adjustable for different drivers.

With these and other objects in view, the invention comprises certain novel parts, elements, units, combinations, constructions, interactions, mechanical movements and functions as disclosed in the drawings together with mechanical and functional equivalents thereof as will be hereinafter more fully described and claimed.

In the drawings:

Figure 1 is a view showing in dotted lines the side elevation of a vehicle with the invention applied thereto.

Figure 2 is a view of the mechanism of each of the similar signals.

Figure 3 is a view of one of the signals shown in vertical section and the associated operating mechanism seen largely in side elevation.

Figure 4 is a sectional view taken on line 4-4 of Figure 3 showing the connection between the knee operated rod and the signal operating rod.

Figure 5 is a view of the exposed side of the signaling hand, showing the reflector carried thereby.

Like characters of reference indicate corresponding parts throughout the several views.

The improved mechanism which forms the subject matter of this application is intended to comprise similar signaling units operated at the front and rear of an automotive vehicle, indicated conventionally in dotted lines at A. The front and rear signaling units are indicated as entireties respectively at B and C. B and C are similar and each comprises a plate or upright 10 mounted upon some rigid part of the vehicle as for instance upon the bumper 11. Extending longitudinally from the unit B to the unit C is a rod 12 carrying upon each end an arm 13 rigidly connected to the rod 12 in any approved manner as by the set

screw 14 and provided at its normally upper end with a wrist pin 15.

Fulcrumed above the shaft 12 on the plate 10 from a fixed pivot 16 is a lever 17 slotted 60 at its lower end, as indicated at 18, to embrace the wrist pin 15.

Pivoted also upon the plate 10 are a pair of arms 19 and 20, their pivoting being respectively adjacent the upper end of the 65 plate at 21 and 22. The arms 19 and 20 are provided with rigid pins 23 and 24 bearing respectively against the opposite sides of the lever 17.

The arms 19 and 20 for the purpose of 70 attracting attention and also more clearly indicating the purpose for which they are designed will terminate in hands 25 and 26 with pointing index fingers 27 and 28, and will also be provided with reflectors 29 of 75 the type already well known for reflecting a light approaching, so that at night, when the vehicle is approaching in the rear, the headlights of the approaching vehicle will illuminate the reflector to attract attention of the 80 operator of the approaching vehicle to the signaling apparatus.

Preferably also, the units will be completed as representing manikins or human figures of some kind, preferably the effigy 85 of a traffic officer.

Upon the steering column 30 of the car, a rod 31 will be mounted to oscillate by means of collars 32 and 33 clamped upon the steering column and furnishing journaling 90 for the shaft 31. Upon the shaft 31 a crank arm 34 will be rigidly but adjustably fixed and from this crank arm 34 a link 35 will extend to a crank arm 36 rigidly secured to the shaft 12.

The adjustment of the crank arm 34 upon the shaft 31 may be accomplished by any usual and ordinary mechanical means, a set screw 37 being shown for the purpose. When the set screw 37 is loosened, the shaft 100 31 may be raised or lowered relative to the clamps 32 and 33 and secured in any approved position so that the ball or other desired termination 38 upon the end of the arm 39 may be so positioned as to be conveniently operated by the swaying motion of the knees of the operator.

In operation, the arms 19 and 20 will normally stand at the position shown in full lines at Figure 2. When the operator is approaching a corner that he proposes to turn, 110 a swaying of the knees in the elected direc-

tion will engage against the ball 38 and will oscillate the shaft 31, therewith the crank arm 34 and by the link connection 35 will also actuate the crank arm 36 and the rod 12. Assuming that the signaling unit shown at Figure 2 is the rear signal and that the proposed turn is a left hand turn, the arm 20 will swing in the direction indicated by the arrow to the dotted line position 20'. 10 This swinging motion is brought about by the oscillation of the rod 12 in the manner hereinbefore described operating upon the crank arm 13, moving it in the direction indicated by the arrow on said arm. This will 15 oscillate the lever 17 in the direction indicated by the arrows, such oscillation being upon the pivot 16. The lever 17 bearing against the pin 24 will serve to move the arm 20 from its normal position to its signaling position indicated by dotted lines. 20 It is obvious, of course, that the oscillation of the rod 31 by the ball 38 in the opposite direction will operate the several parts to throw the arm 19 to signaling position instead of the arm 20. It will be noted also 25 that the arms 19 and 20 are not connected with the lever 17 but that the pins 23 and 24

merely bear against the side edges of said lever and that the lever is, therefore, capable of leaving either of said arms while it actuates the other to signaling position. 30

It is obvious, of course, that the rod 12 extending the entire length of the vehicle, the front and rear signals B and C will be similarly and simultaneously operated. 35

What I claim to be new is:

A traffic signal for vehicles comprising front and rear similar signaling units, a rotatably journaled rod extending longitudinally of the vehicle and operatively connected with both of said signaling units, a shaft extending along the steering column of the vehicle, an arm carried by the shaft positioned normally between the knees of the operator and adapted to be oscillated in either direction by swaying action of the knees, connecting means adapted to transmit the oscillation from the shaft to the rod, and means to adjust the steering column shaft longitudinally for the accommodation of drivers of different physiques. 40

In testimony whereof I affix my signature.

JOHN E. LOCK.
